B. W. JONES

CONTROL SYSTEM FOR ELECTRIC MOTORS

Filed Nov. 23, 1923

Inventor:
Benjamin W. Jones,
by *Alexander S. Jones*
His Attorney.

UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

CONTROL SYSTEM FOR ELECTRIC MOTORS.

Application filed November 23, 1923. Serial No. 676,660.

To all whom it may concern:

Be it known that I, BENJAMIN W. JONES, a citizen of the United States, residing at Schenectady, county of Schenectady, State of New York, have invented certain new and useful Improvements in Control Systems for Electric Motors, of which the following is a specification.

My invention relates to improvements in control systems for electric motors and has for its principal object the provision of means for insuring the starting of the motor with a predetermined initial torque. My invention is of particular utility when embodied in a control system for an adjustable speed motor such as is commonly used in elevator and hoisting service, although my invention also is applicable to the control system of any motor driven apparatus where a smooth and easy starting and control of the apparatus is desirable.

In passenger elevator service, a smooth and easy starting of the elevator car in either direction of travel is essential to avoid serious discomfort to the occupants as well as severe strains and shocks to the elevator mechanism. In order that the driving motor may effect such a smooth and easy starting of the elevator car, the system of control should limit the initial starting torque exerted by the motor within a very narrow range of the torque required merely to balance the car and subsequently increase the motor torque and speed to accelerate the elevator car to running speed.

As is well understood by those skilled in the control of elevators, the starting torque of a variable speed shunt wound direct current motor may be controlled in the above manner by connecting a resistance of a predetermined value in shunt with the motor armature in addition to the usual series connected starting resistance and then starting the motor with weak field, accelerating under full field, and finally weakening the field to bring the motor up to full running speed. Furthermore, such a motor control system is readily adapted for dynamically braking the elevator car in stopping by providing means for varying the resistance in shunt with the motor armature, which then serves as a dynamic braking circuit for the motor, and applying full field to the motor to increase the dynamic braking effect.

However, in the operation of an elevator

provided with such a motor control system it frequently occurs that the car either over-runs or under-runs the selected floor while stopping under the full field dynamic braking action of the motor. To bring the car to the selected floor the operator may then hastily apply power to the motor with the field at full value and the armature shunt resistance at an improper value for smooth starting. This results in the motor exerting a starting torque much greater than desired and the passengers and equipment consequently experience a severe jar or jolt.

My invention contemplates eliminating the possibility of producing such a jolt or jar by providing a control system in which the motor starting switch cannot be operated to connect the motor to the power source until after the field is weakened and the armature shunt resistance is set at the proper value, thus at all times insuring the starting of the motor with weak field and an initial starting torque of a predetermined value.

For a proper understanding of my invention reference is had to the accompanying drawing in which the single figure diagrammatically shows the invention embodied in a master controller type of motor control system for the purpose of explaining the principles thereof. The novel features which I believe to be characteristic of my invention are pointed out with particularity in the appended claims.

Referring to the drawing, the motor 10 having an armature 11 provided with a suitable armature winding and a shunt field winding 12 may be connected by mechanism, not shown, to both drive and dynamically brake an elevator or other apparatus. Motor 10 may be provided with a suitable commutating field 13 if desired, although such a field winding is not essential in carrying out my invention. As indicated in the drawing the shunt field winding 12 is connected in series circuit with a field regulating resistor 14 and the operating winding of a relay 15 across the current supply lines 16 and 17. Relay 15 is biased to the closed position shown and is designed to respond to a field current of a predetermined value to open the relay contacts, and the resistor 14 is proportioned to weaken the field current below this predetermined value while it remains in the field circuit.

The resistors 18, 19, and 20 are connected

through the contacts of electromagnetic switch 21 in a shunt circuit across the motor armature 11 and the commutating field winding 13, to supply a variable resistance load during the dynamic braking operation of the motor and also when properly controlled furnish an armature by-pass resistance of a predetermined value in order to limit the motor starting torque under weak field to a desired value.

Electromagnetic switch 21 is biased to the closed position in which the shunt resistance circuit is established around the motor armature 11 and is actuated to the open position by a suitable operating winding as will more fully appear in connection with the operation of my invention. The resistors 19 and 20 are controlled respectively by the electromagnetic switches 22, and 23, each of which is biased to the closed position to establish a shunt circuit around the resistor as shown, and is provided with a suitable operating winding for actuating the respective switch contacts to the open positions. Resistors 24, 25, and 26 comprise the usual motor starting series resistance and are controlled respectively by the electromagnetic switches 27, 28, and 29, which are biased to the open position, as shown, and are operated to the closed position to short circuit the resistors by suitable operating windings. The several resistors connected in series and shunt with the motor armature are so proportioned that when the armature winding is connected to the supply lines 16 and 17 with the corresponding electromagnetic controlling switches in their respective unenergized positions shown, the armature current is limited to a predetermined value. This value of armature current is such that with the motor field current at the weak field value, the initial starting torque exerted by the motor is just sufficient to move the elevator car slowly and smoothly from a position of rest.

In order to control the field regulating resistance 14, a relay 30 is provided with an operating winding 31, one terminal of which is connected to the resistor 18 and the other terminal is connected to the resistor 26 as indicated. Relay 30 is biased to the open position, as shown, and the operating winding 31 is designed to actuate the relay 30 to close a shunt circuit around resistance 14 when energized by an appreciable voltage from either the current supply lines 16 and 17 during motoring or from the motor during dynamic braking operation.

The electromagnetically actuating reversing switches 32 and 33 are arranged to connect the motor armature winding 11 to the current supply lines 16 and 17 for operation in either direction and are provided with operating windings 34, and 35 respectively. These switches are biased to the open posi-

tion, as shown, and are equipped with the customary mechanical interlock 36 for preventing interference in the control of the motor. It will be observed that one terminal of each of the operating windings 34 and 35 is connected through a common resistance 37 to the current supply line 17. The resistor 37 limits the current supplied to either of the operating windings 34 and 35 to a value which is insufficient to operate the respective switches 32 and 33 from the open position but which is sufficient to maintain either switch in the closed position. A shunt circuit of negligible resistance around the resistor 37 is arranged to be controlled jointly by the contacts of relay 15 and an auxiliary contact mechanism 38 carried by electromagnetic switch 22 in order to permit operation of the reversing switches 32 and 33 from the open positions.

For controlling the energizing circuits of the reversing switch operating windings 34 and 35 as well as the respective operating windings of the electromagnetic switches 21, 22, 23, 27, 28, and 29, a manually operated master controller 39 is provided with the cooperating contacts and segments 40, 41, 42, 43, 44, 45, 46, 47, and 48. These cooperating contacts and segments are arranged so as to engage in a predetermined sequence to energize from the supply lines 16 and 17 first, either the operating winding 35 of reversing switch 33 or the operating winding 34 of reversing switch 32 and then successively energize the operating windings of electromagnetic switches 22, 27, 23, 28, 21, and 29, when the controller 39 is operated from the off position in which it is shown through either the control positions 1 to 7 or 1' to 7' respectively.

Operation.

With the parts as thus constructed and arranged and in their respective positions shown in the drawing the operation of my improved motor control system is as follows:

Assume that the supply lines 16 and 17 are connected to a suitable source of current and the motor 10 is at rest. The motor shunt field is energized through a circuit extending from supply line 16 through the field winding 12, resistance 14, the operating winding of relay 15 to the other supply line 17. With the relay 30 in the open position, resistance 14 reduces the current through the shunt field winding 12 below the predetermined value previously mentioned and the motor field strength will be at the corresponding weak field value. The relay 15, being operatively energized only by a field current below the predetermined value, will remain in the closed position shown. In order to operate the motor 10 in one direction, assume it to be the up direction of the elevator car for the purpose

- of clarity, the master controller 39 is first operated to control position 1. In this position an energizing circuit for the operating winding 35 of reversing switch 33 is completed from supply line 16 through contact and segment 40, contact and segment 41, operating winding 35, auxiliary contact 38 on electro-magnetic switch 22 and the contacts of relay 15 to the other supply line 17.
- Upon response of reversing switch 33, the motor armature winding 11 with the resistor 18 in shunt therewith is connected in series with the starting resistors 24, 25, and 26 across the supply lines 16 and 17. The motor 10 will at once exert an initial torque under weak field of a predetermined value to slowly and smoothly start the elevator car. As the motor is thus started, the operating winding 31 of relay 30 is operatively energized by the voltage of the supply lines 16 and 17 and effects the operation of the relay contacts to closed position. Closure of relay 30 establishes a shunt circuit about the field regulating resistor 14 and the field current is thereby gradually increased from the weak field value to the full field value to correspondingly increase the motor torque and accelerate the car. It should be noted that the gradual increase in the motor field strength begins immediately after the motor is started by closure of the reversing switch 33 and continues during an appreciable time interval due to the inductive action of the shunt field winding. The increased value of field current energizes the operating winding of relay 15 and causes the circuit controlling contacts of the relay to move to open position.
- It should be noted that if, at this point in the acceleration of the elevator car, the controller 39 should be returned to the off position, the operating winding 35 of reversing switch 33 is deenergized and disconnects the motor 10 from the supply lines 16 and 17. The motor 10 then operates as a dynamic brake to retard the movement of the elevator car. During braking the operating winding 31 of relay 30 is energized by the voltage generated by the motor and maintains the shunt circuit around the field regulating resistor 14 closed to effect full field dynamic braking action of the motor. It will be evident that before either of the reversing switches 32 and 33 can again connect the motor armature 11 to the supply lines 16 and 17, the field current must be reduced from the full field value to the weak field value to permit relay 15 to close its contacts and again establish the shunt circuit around the resistor 37. When the motor 10 has brought the elevator car almost to a standstill under full field dynamic braking, the voltage generated by the motor then becomes insufficient to maintain the relay 30 in the closed position. Relay 30 there-
- upon opens the shunt circuit around the field regulating resistor 14 and reduces the field current from the full field value to the weak field value, thus permitting the relay 15 to close according to its bias. Closure of relay 15 again establishes the shunt circuit around the resistor 37 and permits either of the reversing switch windings 34 and 35 to be operatively energized when the master controller 39 is operated from the off position.
- However, if after operation of the master controller 39 to the position 1 as previously described, the controller 39 is then successively moved through the intermediate control positions 2, 3, 4, 5, and 6 to the running position 7; the electromagnetic switches 22, 27, 23, 28, 21, and 29 are successively energized to alternately insert resistance in shunt with the motor armature 11 and remove the resistance in series with the armature, thus gradually accelerating the motor. It will be observed that upon the energization of the operating winding of electromagnetic switch 21 the shunt armature resistance circuit is opened, thus in effect, inserting infinite resistance in shunt with the motor armature. Although upon the opening of switch 21 the operating winding 31 of relay 30 is no longer energized by the full voltage of the supply lines 16 and 17, the voltage drop across the remaining starting resistor 26 will be sufficient to maintain the relay 30 in closed position. After the resistor 26 is finally short circuited by operation of switch 29, the relay 30 thereupon opens and again inserts the resistor 14 in the shunt field circuit and the motor 10 is accelerated to full running speed under weak field.
- To stop the elevator car by dynamic braking at any selected floor, the master controller 39 is thrown from the running position 7 successively through the intermediate positions 6 to 1 to the off position shown. This causes the operating windings of the several electromagnetic switches to be successively deenergized in the reverse order from that in which they were energized. Upon the deenergization of the operating winding of switch 21, this switch closes according to its bias and again establishes the resistance circuit in shunt with the armature; thus causing the motor to operate as a dynamic brake. Closure of switch 21 also impresses the voltage across the motor armature upon operating winding 31 of relay 30. This relay then closes the shunt circuit around the field regulating resistor 14. Since the electromagnetic switch 22 was the first to be energized, it will be released last to short circuit the resistor 19 as well as close the auxiliary contact 38. The motor 10 then operates as a dynamic brake under full field and with a maximum resistance load to bring the elevator

car almost to a standstill. When the voltage generated by the motor becomes insufficient to sustain the relay 30 in circuit closing position, the latter opens according 5 to its bias and once more inserts the resistance 14 in the shunt field circuit to reduce the field strength to weak field value. This permits the relay 15 to close according to its bias and again cooperate with the auxiliary contact 38 on switch 22 to establish 10 the shunt circuit around the resistor 37.

The starting of the motor to operate the elevator car in the down direction is accomplished in substantially the same manner as 15 that just described, with the single exception that in control positions 1' to 7' the cooperating contact and segments 42 are brought into engagement to complete an energizing circuit for operating winding 34 20 of reversing switch 32 extending from supply line 16 through contact and segment 40, contact and segment 42, operating winding 34, contact 38, relay 15 to the other supply line 17. Upon response of reversing switch 25 32 the motor armature, with the resistor 18 connected in shunt circuit therewith, is connected in series circuit with the series starting resistors 24, 25, and 26 across the supply lines 16 and 17 for starting with weak 30 field and the same predetermined initial starting torque in the opposite direction. The deceleration of the motor under dynamic braking to stop the elevator car at any selected floor is likewise similar to that 35 previously described.

While the above described operation is the usual and normal manner in which the motor control system is intended to operate, it should be understood that my improved 40 control system insures at all times that the motor is started with weak field and an initial starting torque of a predetermined amount even under unusual and abnormal operating conditions. For instance, suppose 45 that while the motor is running at full speed in the down direction the operator should instantly shift the master controller 39 from the control position 7' to the control position 1 to quickly effect the reversal of the 50 motor. In this event the operating winding 34 of reversing switch 32 as well as the operating winding of the shunt and series armature resistance controlling switches would be deenergized and the operating 55 winding 35 of reversing switch 33 would be energized. However, it will be seen that the resistance 37 prevents sufficient current from passing through operating winding 35 to effect the closure of reversing switch 33 at 60 this time. Thus, the motor operates under full field as previously described to dynamically brake the elevator car until the speed has been reduced to a value at which the voltage generated by the motor is insufficient 65 to sustain relay 30 in the closed position.

Then relay 30 opens as before and inserts the resistance 14 in the shunt field circuit to reduce the field strength to the weak field value. As soon as the field current has decreased to the predetermined 70 value at which the relay 15 is no longer operatively energized, this relay will close according to its bias. After the relay 15 has completed the shunt circuit around resistor 37, winding 35 is energized by the full voltage across the supply lines 16 and 17 and operates switch 33 to start the motor with weak field and the predetermined resistance in shunt to the armature. Thus it will be seen that a control system embodying my 80 invention always insures that the motor is connected to the source of current with weak field and limited starting torque.

As has been previously pointed out, when the master controller 39 is operated from either direction to the off position, the electromagnetic switch 22 is the last of the armature resistor controlling switches to be deenergized to permit operation according to its bias. Due to this fact, I have found in practice that the single auxiliary contact 38 on the electromagnetic switch 22 is sufficient under all ordinary conditions to insure that the proper armature shunt and series resistors are in circuit for starting the motor with a predetermined armature current. But it will be obvious to those skilled in the art that additional auxiliary contacts may be provided for any selected ones of the other electromagnetic switches and included in the shunt circuit around the resistor 37 should it be desired to positively prevent operation of the reversing switches 32 and 33 from the open position until after the particular switch or switches selected have been deenergized and operated according to their bias. Also it will be understood that after the regulating resistor 100 4 is inserted in the shunt field circuit upon completion of the dynamic braking operation of the motor, an appreciable time may be required for the current in the shunt field circuit to decrease to the weak field value due to the inductive action of the shunt field windings. But until the motor field current is below the predetermined value, the relay 15 will be maintained in the open position and prevent completion of the shunt circuit around resistance 37 and consequently the operative energization 105 of winding 35 of reversing switch 33 even though the contact 38 on switch 22 is in closed position. This feature is of great practical importance since it insures that the motor is always started with weak field.

In accordance with the provision of the patent statutes I have described the principles of my invention together with the apparatus which I now consider to represent the best embodiment thereof but I desire 110 115 120 125 130

to have it understood that the apparatus shown is only illustrative and that the invention may be carried out by other means.

What I claim as new and desire to secure by Letters Patent of the United States, is,—

1. In a control system, the combination with an electric motor, of current controlling means operable to weaken the motor field and to limit the motor starting current under weak field to a predetermined value, switch mechanism for connecting the motor to a source of current, and means for preventing operation of said switch mechanism until after operation of said current controlling means to insure starting of the motor with weak field and limited starting current of a predetermined value.

2. In a control system, the combination with an electric motor having armature and field windings and regulating resistors in circuit therewith, of switch mechanism for connecting the motor to a source of current and controlling the said resistors to vary the motor field strength and starting torque, and means cooperating with the said switch mechanism for insuring the starting of the motor with minimum field strength and starting torque.

3. A control system for an electric motor having armature and field windings and regulating resistors in circuit therewith, comprising a starting switch mechanism for connecting the motor to a source of current, electromagnetic means for controlling the said starting switch mechanism and the said armature and field resistors, and means cooperating with the said electromagnetic means for insuring the starting of the motor with weak field and starting torque of a predetermined value.

4. A control system for an electric motor having armature and field windings and regulating resistors in circuit therewith, comprising switching means for controlling the said resistors to limit the motor starting torque under weak field to a predetermined value, electrically actuated switch mechanism for connecting the motor to a source of current, and means for operatively energizing the said electrically actuated switch mechanism controlled by the said switching means to insure the starting of the motor with weak field and starting torque of a predetermined value.

5. A control system for a reversible electric motor having armature and shunt field windings and regulating resistors in circuit therewith, comprising electromagnetically actuated switch mechanism for connecting the motor to a source of current, a plurality of mechanically independent switches for controlling the said resistors to vary the motor field strength and starting torque between minimum and maximum values, and

means dependent upon the operation of said independent switches to the minimum field and starting torque positions for operatively energizing the said electromagnetically actuated switch mechanism.

6. A control system for an electric motor having armature and field windings and resistors in circuit therewith, comprising, an electromagnetically actuated switch mechanism for connecting the motor to a source of current, a switch for controlling the armature resistor to vary the starting current through the said armature winding, a second switch for controlling the field resistor to vary the current through the said field winding, a relay connected in circuit with the said field winding and operatively energized responsively to a predetermined current, and electrical connections for energizing the said electromagnetically actuated switch mechanism jointly controlled by the said relay and the said armature resistor controlling switch to insure the starting of the motor with weak field and limited starting torque of a predetermined value.

7. A control system for an electric motor having armature and shunt field windings and regulating resistors in circuit therewith comprising, electromagnetically operated starting switch mechanism for connecting the motor to a source of supply, a resistor in circuit with the operating winding of said mechanism for preventing operation thereof, switching means for controlling the said armature and field resistors to weaken the motor field and limit the motor starting torque under weak field to a predetermined value, and switch mechanism and electrical connections controlled by the said switching means for establishing a shunt circuit around the said operating winding resistor to permit starting the motor with weak field and limited starting torque of a predetermined value.

8. A control system for an electric motor having armature and shunt field windings comprising a resistor in shunt circuit with the said armature winding, a resistor in series circuit with said field winding and a source of current, electromagnetically operated starting switch mechanism for connecting the motor to the said source of current, a resistor in series circuit with the operating winding of said mechanism for preventing operation thereof, switching means for opening a shunt circuit around the said field resistor and closing a shunt circuit around the said armature resistor to weaken the motor field and limit the starting torque of the motor under weak field to a predetermined value, and switch mechanism and electrical connections controlled by said switching means for establishing a shunt circuit around the said operating winding

- 6
- resistor to permit starting the motor with weak field and starting torque of a predetermined value.
9. A control system for an electric motor having armature and shunt field windings, comprising, a resistor in shunt circuit with the said armature winding, a resistor in series circuit with said field winding and a source of current, electromagnetically actuated switch mechanism for connecting the motor armature winding to the said source of current, a switch for closing a shunt circuit around the said armature resistor, a second switch for opening a shunt circuit around the said field resistor to reduce the motor field current below a predetermined value, a relay connected in the said field circuit and operatively energized responsive- 10 to current above the said predetermined value, and electrical connections for energizing the said electromagnetically actuated switch mechanism jointly controlled by said armature resistor controlling switch and said relay for preventing actuation of said switch mechanism until after both the closure of said shunt circuit around the said armature resistor and the reduction of the motor field current below the said predetermined value.
10. A control system for an electric motor having armature and shunt field windings, comprising, a resistor in shunt circuit with the said armature winding, a resistor in series circuit with said field winding and a source of current, electromagnetically oper- 15 ated switch mechanism for connecting the motor armature winding to the said source of current, a resistor in circuit with the operating winding of said mechanism for preventing operation thereof, a switch for opening a shunt circuit around the said field resistor to reduce the motor field current, a relay connected in the said field circuit and operatively energized responsive- 20 to current above a predetermined value, a second switch for closing a shunt circuit around the said armature resistor to limit the motor starting torque under reduced field to a predetermined value, and switch mechanism and electrical connections jointly controlled by said relay and said armature resistor controlling switch for establishing a shunt circuit around the said operating winding resistor after both the closure of said shunt circuit around the said armature resistor and the reduction of the motor field current below the said predetermined value to permit starting the motor with predetermined field and starting torque.
11. A control system for a reversible electric motor having armature and shunt field windings and resistors in circuit therewith, comprising electromagnetically actuated reversing switches for connecting the motor to a source of current for operation in either direction, an electromagnetically actuated switch for closing a shunt circuit around the said armature resistor, a second electromagnetically actuated switch for opening a shunt circuit around the said field resistors 70 to reduce the motor field current, a master controller for controlling the actuation of the said electromagnetically actuated switches, and means, including a relay responsive to a predetermined current through the shunt field winding and auxiliary switch mechanism operated by said armature resistor controlling switch, for preventing actuation of said reversing switch mechanisms until after the closure of the said shunt circuit around the said armature resistor and the reduction of the shunt field current to the said predetermined value.
12. A control system for a reversible electric motor having armature and field windings adapted for dynamic braking, comprising, a resistor in shunt circuit with the said armature winding, a field regulating resistor, switching means for controlling the said resistors to stop the motor under full field 85 dynamic braking action and to limit the motor starting torque under weak field to a predetermined value, reversing switches for connecting the motor armature winding to a source of current for operation in either 90 direction, and means cooperating with the said switching means and the said reversing switches to insure the starting of the motor with weak field and a limited torque of a predetermined value.
13. A control system for a reversible electric motor having armature and field windings adapted for dynamic braking, comprising a resistor in shunt circuit with the said armature winding, a field regulating resistor, switching means for controlling the said resistors to stop the motor under full field dynamic braking action and to limit the motor starting torque under weak field to a predetermined value, electrically actuated reversing switches for connecting the motor armature winding to a source of current for operation in either direction, and means for operatively energizing the said electrically actuated reversing switches controlled by said switching means to insure the starting of the motor with weak field and limited torque of a predetermined value.
14. A control system for a reversible electric motor having armature and field windings adapted for dynamic braking, comprising, a resistor in shunt circuit with the said armature winding, a field regulating resistor, switching means for controlling the said resistors to stop the motor under full field dynamic braking action and to limit the motor starting torque under weak field to a predetermined value, electromagnetically operated reversing switch mechanism for connecting the motor armature winding to 120
15. A control system for a reversible electric motor having armature and field windings adapted for dynamic braking, comprising, a resistor in shunt circuit with the said armature winding, a field regulating resistor, switching means for controlling the said resistors to stop the motor under full field dynamic braking action and to limit the motor starting torque under weak field to a predetermined value, electromagnetically operated reversing switch mechanism for connecting the motor armature winding to 125
16. A control system for a reversible electric motor having armature and field windings adapted for dynamic braking, comprising, a resistor in shunt circuit with the said armature winding, a field regulating resistor, switching means for controlling the said resistors to stop the motor under full field dynamic braking action and to limit the motor starting torque under weak field to a predetermined value, electromagnetically operated reversing switch mechanism for connecting the motor armature winding to 130

- a source of current for operation in either direction, a resistor in circuit with the operating winding of said mechanism for preventing operation thereof, and switch mechanism and electrical connections controlled by the said switching means for establishing a shunt circuit around the said operating winding resistor to permit the starting of the motor with weak field and limited torque 10 of a predetermined value.
15. A control system for a reversible electric motor having armature and shunt field windings adapted for dynamic braking, comprising, a resistor in shunt circuit with the said armature winding, a resistor in series circuit with said field winding and a source of current, electromagnetically actuated reversing switch mechanism for connecting the motor to the said source of current for operation in either direction, a switch for closing a shunt circuit around the said armature resistor to regulate the dynamic braking effect of said motor and to limit the motor starting torque, a second 20 switch for opening a shunt circuit around the said field resistor to reduce the motor field current below a predetermined value, a relay connected in the said field circuit and operatively energized responsively to current above the said predetermined value, and electrical connections for operatively energizing the said electromagnetically actuated reversing switch mechanism jointly controlled by said first switch and said relay 25 for preventing actuation of said reversing switch mechanism until after both the closure of said shunt circuit around the said armature resistor and the reduction of the motor field current below the said predetermined value.
- 30 16. A control system for a reversible electric motor having armature and shunt field windings and adapted for dynamic braking, comprising, a resistor in shunt circuit with the said armature winding, a resistor in series circuit with said field winding and a source of current, electromagnetically operated switch mechanism for connecting the motor armature to the said source of current for operation in either direction, a resistor in circuit with the operating winding of said mechanism for preventing operation thereof, a switch for opening a shunt circuit around the said field resistor to weaken the motor field, a relay connected in the said field circuit and operatively energized responsively to current above a weak field value, a second switch for closing a shunt circuit around the said armature resistor to regulate the dynamic braking effect of said motor and to limit the motor starting torque under weak 35 field to a predetermined value, and switch mechanism and electrical connections jointly controlled by the said relay and the said armature resistor controlling switch for establishing a shunt circuit around the said resistor to permit the starting of the motor with weak field and limited torque of a predetermined value.
- 40 17. In a control system, the combination with an electric motor having a shunt field winding and a resistor in circuit therewith, of switching means for controlling the said resistor to vary the field current of said motor, an electrically actuated switch for connecting the motor armature to a source of supply, a relay for controlling the energizing circuit of said switch, and electrical connections whereby the said relay is operatively energized responsively to the motor field current for preventing actuation of the said starting switch.
- 45 18. In a control system, the combination with an electric motor having a shunt field winding and a field resistor in circuit therewith, of switching means for controlling the said resistor to vary the field current of said motor, an electromagnetically operated starting switch for connecting the motor armature to a source of supply, a resistance in circuit with the operating winding of said switch for preventing operation thereof, and a relay connected in the said field circuit and responsive to current below a predetermined value for closing a shunt circuit around the said resistance to permit operation of the said starting switch.
- 50 19. In a control system, the combination with an electric motor having a shunt field winding and a dynamic braking circuit, of a switch mechanism for connecting the motor to a source of supply for operation in either direction and for disconnecting the motor therefrom for dynamic braking operation, of a resistor in circuit with the said field winding, an electromagnetic switch biased to open position and operable to closed position for controlling the said resistor to vary the field current of said motor and having an operating winding energized responsively to the voltage of the source during motoring operation and to the voltage generated by the motor during dynamic braking operation, and a relay connected in the said field circuit and operatively energized responsively to field current above a predetermined value for preventing operation of the said switch mechanism to connect the motor to the source.
- 55 110 115 115 In witness whereof, I have hereunto set my hand this 22nd day of November, 1923.
- BENJAMIN W. JONES.
